SEPARABLE SKI BINDER

Edwin A. Parish, Walla Walla, Wash., assignor of seventeen per cent to Adam H. Schwandt and thirty-three per cent to Howard V. Schwandt, both of Weston, Oreg.

Application June 22, 1936, Serial No. 86,547

10 Claims. (Cl. 280—11.35)

This invention relates to separable ski binders and has for one of its objects to provide a binder that is automatically separable under certain conditions and that may be separated or assembled manually.

Another object of the invention is to provide a separable binder constructed to provide extreme transverse rigidity and yet afford the maximum in vertical flexibility.

10 A further object of the invention is to provide a separable binder which will rapidly and automatically become separable from a fall whether the fall is forwardly or sidewise.

15 A further object of the invention is to provide a separable binder consisting mainly of two parts, one of which is permanently secured to a ski and the other of which removably attached to a shoe and in such a manner that upon the attainment of a predetermined angle of one with 20 the other the two parts will immediately separate releasing the ski from the shoe of the skier.

25 A further object of the invention is to provide a separable ski binder in which the operative parts of the locking means will be enclosed against the effect of snow and the elements.

30 A further object of the invention is to provide a separable ski binder that may be reassembled in a most comfortable manner without bending the foot.

With these and other objects in view reference is now had to the accompanying drawings in which

35 Fig. 1 is a side elevation of the invention;

Fig. 2 is a plan view of the invention;

Fig. 3 is a side elevation of the securing plate showing a part of the locking means;

Fig. 4 is a plan view thereof showing the engaged position of the locking bar;

40 Fig. 5 is a similar view to Fig. 4 but showing the locking bar in the released position;

Fig. 6 is a perspective view of a fragment of one form of side iron;

Fig. 7 shows a modification thereof; and

45 Fig. 8 is a line drawing representing the angle attained at the moment of separation.

Fig. 9 is a vertical longitudinal section of the device taken on the line 9—9 of Fig. 2;

Fig. 10 is a vertical transverse section of the 50 device taken on the line 10—10 of Fig. 2;

Fig. 11 is a vertical transverse section of the device taken on the line 11—11 of Fig. 2; and

Fig. 12 is a vertical transverse section of the device taken on the line 12—12 of Fig. 2.

55 Having reference to the drawings like numerals

refer to like parts through the several views and the numeral 1 refers to the binder in its entirety which consists in general of a foundation housing 2 and a foot plate 3 and these will now be explained:

The foundation housing 2 is so called as it is rigidly secured to a ski 4, and consists of a securing plate 5 provided with a snow tight cover 6, removably secured thereto, which serves to enclose an operating mechanism contained therein, 10 and has its uppermost surface curved slightly to provide a toe plate 7 which, with the operating mechanism, will be presently explained, and the toe plate forms a support for the toe of the shoe 8 when the binder is secured to the foot of the 15 skier, and this cover is stream lined, as shown, to reduce the frictional resistance of the snow.

The securing plate 5 in itself consists of a bottom plate 9 preferably approximating the width of the ski and is provided with longitudinal dimensions whereby when secured to the ski, by screws (not shown) through the holes 10 represented by the concentric circles, as shown in Figs. 4 and 5, will become a part of the ski so far as rigidity is concerned.

25 Rearward of the securing plate 5, and formed integral therewith, are perpendicularly disposed guide posts 11, the rearward pair of which is provided with transversely aligned hinge sockets 12, one on each side of said securing plate, and 30 in addition a runway 13, shown dotted, is provided in the posts 11, in parallel relation to the securing plate 5, wherewith to form a guide for the longitudinal movement of a U shaped locking bar 14 whose vertical arms 15 are extended rearward for slidable movement in the runways 13 to cover the sockets 12 which form one part of a transversely positioned hinge.

The arms 15 are continued to form the base 16 of the U, and to the base is rigidly secured a 40 releasing bar 17 having a forwardly extended projection 18 adapted to pass through the cover plate 6 when assembled, upon the end of which a knob 19 is attached as represented by the ball in Figs. 1 and 2 for the manual operation of that 45 member.

The releasing bar 17 is also extended rearward from the base 16 of the U to provide an interior projection 20 and is guidedly supported by a rear guide post 21 and a forward guide post 23 in 50 which it is slidably mounted, while a spring 22, which is mounted on the releasing bar 17, bears against the forward releasing bar guide post 23 to yieldingly maintain the locking bar 14 in the secured position, shown in Fig. 4, thus the move- 55

ment of the locking bar with the releasing bar will be uniform and, as is plainly evident from the drawings, the locking and releasing bars may be moved manually by the knob before mentioned, or automatically in a manner to be presently explained.

The foot plate 3 is of any cross section designed for lightness and strength and has its forward end 24 raised to the general level of the cover 10 plate 6 of the foundation housing 2 and its rearward end is equipped with a heel plate 25, adjustably mounted thereon in a manner to be explained, for longitudinal adjustment, and this plate is of the same level as the forward end 15 24 of the foot plate and foundation, all of which forms a support for the foot of the skier.

Attached to the rear or raised portion of the heel plate 25, by a rivet B or other suitable means, not shown, is a strap 26 (represented in part by 20 the diagonally positioned and parallel dotted lines) to provide means for holding the foot of the skier back against the raised portion, which raised portion provides a stop 27 against which the heel 28 will rest.

25 The heel plate 25 terminates forwardly in a channel C in which adjustable heel irons 29 are secured to the heel plate 25, in a manner to be explained, in Fig. 10, and may be of any usual construction or as shown in Fig. 2, and in part 30 in the perspective views in Figs. 6 and 7, that shown in Figs. 6 and 2 corresponding in part. The heel irons consist of opposed horizontal channel sections 30 provided with a slot extended to the inner end thereof, represented as at 31, and 35 these sections are slidably mounted in the channel C and secured by a bar 32 mounted in and filling said sections 30 to be rigidly tightened against the sections by the screws 33 which pass through the bar and the slot 31 of the channel 40 sections for frictional securement by a nut D against the inner side of the channel C. A third and centrally disposed screw 34 assists to bind the sections 30 in the channel C of the heel plate 25 by passing through the slot A to adjustably 45 secure the whole to the longitudinal piece 35 of the foot plate, in the usual manner of such construction, thereby providing, with the screw 36 similarly mounted to the rear of and in line with the last mentioned screw 34, to maintain the heel 50 plate in positive longitudinal alignment with the foot plate and with the heel irons perpendicular to the longitudinal axis thereof. The heel irons are also provided with the usual vertical and oppositely positioned jaws 37 with which to engage the sides of the heel.

In the forward raised portion 24 of the foot plate side irons 38, with similarly positioned and constructed jaws 39 are provided, with the exception that these jaws have an inwardly directed 60 horizontal portion 40 having a lip 40' designed to seat on top of the sole 41 of the shoe and the slot or groove 31' in the iron, shown in Fig. 6, is designed to facilitate vertical adjustments secured by the screw 42 to accommodate soles of 65 different thickness between the lip 40' and the horizontal portion 24.

It is now apparent that when the side irons are secured to the sole of the shoe and with the heel iron brought against the heel thereof that 70 when the strap is brought over the instep the foot plate will positively respond to the slightest transverse movement of the foot.

The forward portion 43 of the footplate is extended and is preferably drilled to receive a steel 75 or hardened hinge pin 44 which is extended trans-

versely to substantially the outer edge of the binder and is secured in that position by the set screws represented by the circles 45.

Obviously different methods may be used to provide the hinge pin. The methods shown however are my preferred form as absolute rigidity is thus obtained and which rigidity in a horizontal plane is highly essential in the binder.

Centrally disposed on the pin 44 is a cam 46 whose position with respect to the foot plate is 10 maintained absolute by a set screw 46' whereby to secure the cam rigidly in a selected position on the pin 44, and consequently with respect to the foot plate 3.

From the above it is obvious that by raising 15 the heel plate 25 of the foot plate to the position indicated in Fig. 8, the releasing bar 17 will be automatically forced forward by the cam, as shown in Fig. 5, against the tension of the spring thus uncovering the hinge sockets and permitting the pin to be withdrawn.

It is now apparent that to assemble the two parts, i. e. the foot plate and the foundation housing, that with the foot plate secured to the shoe, and the projecting ends of the pin 44 placed in 25 registerable position with respect to the sockets of the securing plate, that by withdrawing the releasing bar manually the pin will seat in the sockets to be secured therein when the releasing bar is released for the purpose.

It is also apparent that any rotative movement of the foot will impart the same movement to the ski and any twist of the ankle or any movement required, as to provide say for edging, will also be communicated promptly to the ski. The 35 end of the interior projection of the releasing bar is preferably rounded as shown and rests at all times against the face of the cam being held in contact therewith by the resiliency of the spring; therefore, with the cam face properly designed 40 movement of the foot plate in a vertical arc about the pin will move the releasing bar automatically as the heel is raised, and movement of this bar will withdraw the locking bar to uncover the said 45 sockets and by setting the cam properly the foot plate will be automatically released from the foundation house when a predetermined angle of one part (the foot plate) with another part (the housing) is attained, and simultaneous pressure forward of the toe against the curve of 50 cover plate, or toe rest, and the resiliency of the sole of the shoe will force the separation of the two parts the moment the lock is released.

It is now obvious that by transversely positioning the sockets and pins which go to form the 55 hinge joining the two parts of the binder, and constructing that hinge in the substantial manner shown, that I have provided what might be termed a "flexible-rigid" binding, the flexibility enabling the Telemark positions to be readily accomplished without fear of separation of the parts until such a movement of the foot, as might be caused by a fall, would be reached; then and then only would separation occur.

In hill climbing, or side stepping, or herring 65 boning, or in the kick turn, or even in landings and the jump, the toe is never bent to an angle that would release the foot from the ski. At the same time the transverse rigidity is so positive that the ski is under more positive control than when the foot is secure to the ski by a binding formed chiefly of leather straps. This is true in traversing, in the side step, in stemming, and the stem break. The device, therefore, is highly efficient in operation, and in addition when separa- 70 75 75

tion occurs the foot plate remains secured to the shoe and will thus provide a non-slipping adjunct that will materially assist the act of walking over the snow, should such act be necessary.

5 Having thus described my invention, I claim
1. A separable ski binder, consisting of a foundation housing securable to a ski, and a foot plate attached to said housing and arranged therewith for automatic release therefrom when 10 a predetermined angle of one with the other is attained.

10 2. A separable ski binder, consisting of a foundation housing and a foot plate hingedly attached together transversely and provided with automatic releasable locking means, means to secure 15 said housing to a ski, and means to adjustably secure the foot plate to a shoe.

3. In a separable ski binder, a foundation housing, consisting of a securing plate, securable to 20 a ski, and a streamlined cover plate removably secured to said securing plate, and containing a lock, and a foot plate securable to the shoe and hingedly attached to said housing, for secure- 25 ment thereto by said lock, for automatic release therefrom when a predetermined angle of one part with the other is attained.

4. In a separable ski binder, a foundation housing, consisting of a securing plate, rigidly securable to a ski, and provided with a transverse hinge socket formed in said securing plate, and containing a locking bar registerable with said hinge socket, a cover plate removably secured to 30 said securing plate, to enclose said lock, and a foot plate securable to a shoe and hingedly attached to said housing by said lock, and means to automatically operate said lock to release the 35 foot plate when a predetermined angle of one part with the other is attained.

5. In a separable ski binder, a foundation housing consisting of a securing plate, means contained in said housing to secure said plate to a ski, a transversely directed hinge socket formed in said plate, a locking bar registerable with said socket, and a cover plate removably secured to 40 said securing plate to enclose said lock, and a foot plate provided with adjustable heel and side irons, and transversely directed hinge pins engageable with the hinge socket of said foundation housing, for securement therein by said lock, and means adjustably attached to said foot plate to automatically release the foot plate from said housing when a predetermined angle of one part with the other is attained.

6. In a separable ski binder, a foundation housing consisting of a securing plate, means contained in said housing to secure said plate to a ski, transversely aligned hinge sockets formed in said plate, a locking bar contained in said housing and disposed to register with said sockets, and a cover plate removably secured to said securing plate to inclose said lock, and a foot plate, provided with adjustable heel and side irons, and provided with transversely directed hinge pins 45 engageable with the hinge sockets of said foundation housing for securement therein by said lock, and means adjustably attached to said foot plate to automatically release the said foot plate from said housing when a predetermined angle of one part with the other is attained.

7. In a separable ski binder, a foundation housing consisting of a securing plate, guide posts formed integral with and perpendicular to said securing plate, a transversely aligned socket 50 formed in two oppositely positioned posts, a lock-

ing means slidably mounted in said guide posts, means to manually release said locking means, and a cover plate removably secured to said se- 5 curing plate and inclosing said lock, and a longitudinally adjustable foot plate provided with ad- justable heel and side irons, and provided with a transversely directed hinge pin extended to sides of said foot plate and disposed for secure- 10 ment in said sockets by said lock, and an ad- justably mounted cam carried by said foot plate and disposed to register with and automatically release the foot plate therefrom when a pre- 15 determined angle of one part with another is attained.

8. In a separable ski binder, a foundation hous- 15 ing, consisting of a securing plate provided with guide posts formed integral with and perpendicular to said securing plate, two oppositely positioned of said posts having transversely aligned 20 sockets formed therein, a locking means slidably and guidedly mounted in said posts and comprising a yieldingly operable locking bar extended to cover said sockets, and a releasing bar extended forwardly for manual operation and projected rearwardly for automatic operation, and a cover 25 plate removably secured to the securing plate to inclose said lock and provide a toe support for said binder, and a longitudinally adjustable foot plate, provided with adjustable heel and side irons, a transversely directed hinge pin extended 30 to the sides of said foot plate, for hinged secure- 35 ment in said sockets by said locking bar, and an adjustably mounted cam, carried by said foot plate and registerable with the rearwardly projected locking bar, to automatically release the foot plate from said housing when a predetermined angle of the foot plate with the foundation housing is attained.

9. In a separable ski binder, a foundation hous- 40 ing, means for securing the housing to a ski, and containing hinge sockets, a locking means, slid- 45 ably and guidedly contained in said housing, and including a yieldingly operable locking bar, ex- tended to cover said sockets, a releasing bar ex- 50 tended forwardly for manual operation, and pro- jected rearwardly for automatic operation, said housing forming a toe support for said binder, and a longitudinally adjustable foot plate, adapt- 55 ed for securement to a shoe, and provided with forwardly disposed and transversely directed hinge pins extended for hinged engagement with and for securement in said sockets by said lock- 60 ing means, and an adjustably mounted cam dis- posed forwardly in said foot plate, and register- 65 able operably with the rearwardly projected re- leasing bar, to automatically release the foot plate from said housing when a predetermined angle of the foot plate with the housing is at- 70 tained.

10. In a separable ski binder, a foundation hous- 60 ing, consisting of a securing plate, provided with guide posts disposed on each side of said plate, and containing transversely positioned hinged sockets formed in said posts, a locking 65 means, consisting of a U shaped locking bar, guidedly mounted in said posts, with the vertical arms of said U extended rearward to cover said sockets, and a yieldingly mounted releasing bar secured to said locking bar, and provided at one end with an exterior projection for manual op- 70 eration, and an interior projection for automatic operation of said locking bar, a cover plate removably secured to said securing plate, to inclose said lock, and to provide a toe support, and a foot plate adjustably attachable to a shoe, and 75

adapted to provide a non-slipping adjunct thereto, and provided with forwardly disposed hinge pins extended for hinged engagement with and for securement in said socket, by said locking bar, and provided with a forwardly disposed and adjustably mounted cam, for operable register with

the interiorly projected releasing bar, for the automatic release of the foot plate from said housing when a predetermined angle of the foot plate with the housing is attained.

EDWIN A. PARISH.
